UNITED STATES PATENT OFFICE.

ALEXANDER McDONALD, OF PITTSBURGH, AND WILLIAM O. SMITH, OF WILKINSBURG, PENNSYLVANIA, ASSIGNEES OF SEVENTY PER CENT TO JOHN C. YOUNG, OF PITTSBURGH, PENNSYLVANIA.

CHIMNEY VENTILATOR.

Application filed February 27, 1928. Serial No. 81,121.

This invention relates to chimney ventilators, and has for one of its objects to provide a novel, simple and inexpensive device of this character which shall be adapted to deflect the wind impinging against the same in an upward direction so as to create a positive upward draft within the chimney.

A further object of the invention is the provision of a chimney ventilator which shall be adjustable so as to permit of its use in connection with a chimney of any size.

With the foregoing and other objects in view the invention consists of the construction, combination and arrangement of parts hereinafter fully described and claimed, and illustrated in the accompanying drawing, wherein:

Figure 1 is a sectional view taken on a plane extending vertically and centrally through a chimney ventilator constructed in accordance with our invention,

Figure 2 is a top plan view of the chimney ventilator,

Figure 3 is a view in side elevation of a slightly modified form of the chimney ventilator,

Figure 4 is a top plan view of the modified form of the chimney ventilator.

Figure 5 is a sectional view taken on a plane extending vertically and centrally through a further modified form of the chimney ventilator,

Figure 6 is a top plan view of the chimney ventilator shown in Figure 5, and

Figure 7 is a detail sectional view taken on the plane indicated by the line 7-7 of Figure 6.

Corresponding and like parts are referred to in the following description, and designated in the several views of the accompanying drawing, by similar reference characters.

Referring to the drawing by reference characters, and particularly to Figures 1 and 2, 1 designates a pipe which is adapted to have a snug fit in the chimney and 2 an apron which is adapted to overlie the upper end of the chimney. The pipe 1 is rectangular in plan and is of sectional formation to permit its horizontal dimensions to be varied. The sections 1^a of the pipe 1 are similar and of angular form in cross section, and are arranged in assembled relation with their side edges overlapping. The pipe sections 1^a are secured together for relative lateral adjust-

ment by bolts 3 which extend through horizontally disposed slots 4 in the overlapping portions of the sections. The apron 2 is of truncated pyramidal form, and the upper end thereof is secured to the pipe 1 below the upper end of the pipe by the bolts 3. The apron 2 is also of sectional formation to permit its horizontal dimensions to be varied in adapting the device for application to the chimney. The apron sections 2^a are similar and of angular formation in horizontal section, and are arranged in assembled relation with their side edges overlapping. The apron sections 2^a are provided with horizontal slots 5 for the reception of the bolts 3.

The upper end of the pipe 1 constitutes a vertical extension of the apron 2, and said extension, together with the apron, deflect the air impinging against the same in an upward direction with the result that a positive upward draft is created within the chimney.

As shown in Figures 3 and 4, the ventilator may consist merely of a hollow truncated pyramidal member 6 provided at its upper end with a vertical extension 7, and adapted to be positioned upon and secured to the upper end of the chimney. The member 6 comprises sections 6^a and the vertical extension comprises sections 7^a. These sections are similar and of angular formation in horizontal section and are secured together in a manner to permit the horizontal dimensions of the device to be varied so as to adapt it for application to a chimney of any size. The sections are assembled with their sides in overlapping relation and are secured together by bolts 8 which pass through horizontal slots 9 in the sections 7^a.

The ventilator shown in Figures 5, 6 and 7 comprises a truncated pyramidal member 10 provided at its upper end with a vertical extension 11 and a truncated pyramidal outer member 12 provided at its upper end with a vertical extension 13. The vertical dimensions of the outer member 12 and its extension 13 are less than the respective corresponding dimensions of the inner member 10 and its extension 11, and the lower edge of the outer member is spaced upwardly from the corresponding edge of the inner member and the upper edge of the extension of said outer member is spaced below the corresponding edge of the extension of the inner member. The outer member 12 and extension 13 are

secured in spaced relation to the inner member 10 and extension 11 by bolts 14 and spacing sleeves 15. The inner member 10 and its extension 11 are made of similar sections 10^a and 11^a which are of angular formation in cross section, and the outer member 12 and extension 13 are made of similar sections 12^a and 13^a which are of angular formation in cross section. The parts are assembled with their edges in overlapping relation and the sections thereof secured against casual relative movements by the bolts 14 which pass through slots 16 in the sections. This device is also adjustable and is adapted for application to a chimney of any size, and the inner member 10 thereof is adapted to be positioned upon and secured to the upper end of the chimney.

From the foregoing and accompanying drawing, it will be apparent that each form of the ventilator embodies upwardly and inwardly inclined surfaces at the upper ends of which is a vertical extension. These surfaces and extensions function jointly to deflect the wind upwardly in such a manner as to create a positive upward draft within the chimney. Furthermore all forms of the ventilator are adjustable so as to permit them to be used in connection with chimneys of different sizes. The sections of the respective ventilators may be readily adjusted and secured in adjusted position against casual relative movement. The deflector shown in Figures 5, 6 and 7 is especially adapted for use under conditions that require an exceptionally strong draft, and such draft will be created in the chimney in connection with which this device is used as the wind increases in velocity as it passes upwardly between the inner and outer members 10 and 12 and their vertical extensions 11 and 13. The increase in velocity of the wind is effected by the angular arrangement of the member 12 with respect to the member 10, the former inclining downwardly and outwardly from its upper to its lower end with respect to the latter, and the wind reaches its maximum velocity in the space between the extensions 11 and 13.

It should be understood that the drawing is merely illustrative and does not pretend to give exact proportions. Furthermore, the said drawing is illustrative of a preferred construction, it being our expectation that various changes and modifications may be made without departing from the spirit and scope of our invention.

What is claimed is:—

1. A ventilator comprising a hollow inner member of sectional formation, an upwardly and inwardly inclined hollow

outer member of sectional formation and shorter than the inner member, the outer member extending from a plane below the upper end of the inner member to a plane 65 above the lower end of the inner member, the sections of each member having their side edges arranged in overlapped relation and provided in said portions with horizontally disposed registering slots, and bolts 70 passing through the slots to support the outer member from the inner member and to secure the sections of the members together for relative lateral adjustment.

2. A ventilator comprising an upwardly 75 and inwardly inclined hollow inner member, an upwardly and inwardly inclined hollow outer member shorter than the inner member, the members being arranged in spaced relation and the outer member being arranged 80 at an angle to the inner member and extending from a plane below the upper end of the inner member to a plane above the lower end of the inner member, the upper ends of the members being vertically arranged and relatively spaced and the upper end of the inner member being longer than and extending 85 above the upper end of the outer member, and means for securing the members together.

3. A ventilator comprising an upwardly and 90 inwardly inclined hollow inner member, an upwardly and inwardly inclined hollow outer member shorter than the inner member, the members being relatively spaced and angularly related and the outer member extending 95 from a plane below the upper end of the inner member to a plane above the lower end of the inner member, the members being of sectional formation and provided with vertically arranged and relatively spaced upper 100 ends of relatively different heights, and means securing the members together and securing the sections thereof together for relative lateral adjustment.

4. A ventilator comprising a hollow inner 105 member of sectional formation, an upwardly and inwardly inclined hollow outer member of sectional formation and shorter than the inner member, the outer member extending from a plane below the upper end of the inner member to a plane above the lower end of the inner member, the sections of each member having their side edges arranged in adjustable overlapping relation, and fastening devices securing the members of each 110 section in their adjustment and also connecting the sections together and maintaining them in relative position.

In testimony whereof we affix our signatures.

ALEXANDER McDONALD.
WILLIAM O. SMITH.
